US00D332252S

United States Patent [19]

Kovacik et al.

[11] Patent Number: Des. 332,252

[45] Date of Patent: ** Jan. 5, 1993

[54] FEMALE ELECTRICAL CONNECTOR WITH
OVERLOAD PROTECTION

[75] Inventors: James D. Kovacik, Brecksville;
Thomas J. Blanch, Hudson; Paul S.
Blanch, Valley View, all of Ohio

[73] Assignee: Alert Safety Lite Products Co., Inc.,
Bedford Heights, Ohio

[**] Term: 14 Years

[21] Appl. No.: 655,895

[22] Filed: Feb. 14, 1991

[52] U.S. Cl. D13/142; D13/143

[58] Field of Search D13/137, 139, 140, 141,
D13/142, 143, 160; 439/620, 621, 622; 337/197

CLAIM

The ornamental design for a female electrical connector with overload protection, as shown and described.

DESCRIPTION

FIG. 1 is a left side elevational view of a female electrical connector with overload protection showing my new design;

FIG. 2 is a rear elevational view thereof;

FIG. 3 is a front elevational view thereof;

FIG. 4 is a right side elevational view thereof;

FIG. 5 is a top plan view thereof;

FIG. 6 is a bottom plan view thereof;

FIG. 7 is a left side elevational view of a female electrical connector with overload protection showing a second embodiment of the design;

FIG. 8 is a rear elevational view thereof;

FIG. 9 is front elevational view thereof;

FIG. 10 is the right side elevational view thereof;

FIG. 11 is a top plan view thereof; and,

FIG. 12 is a bottom plan view thereof.
